CUTOFF AND TRANSFER MECHANISM

Richard Lester Wileox, Waterbury, Conn., assignor to The Waterbury Farrel Foundry and Machine Company, Waterbury, Conn., a corporation of Connecticut

Application April 2, 1942, Serial No. 437,417

26 Claims. (Cl. 10—25)

This invention relates to new and useful improvements in cut-off and transfer mechanisms, particularly as applied to a header, upsetting machine or the like.

The principal object of this invention is to provide mechanisms of this character so constructed and operating as to permit an increase in the speed and output of the machine with which it is associated. Further objects are to provide holding and cutting means which will rigidly grip and securely hold, while being severed, that portion of a wire, rod or the like, to be cut, such means being composed of plural parts which open slightly and permit the wire to pass therebetween, then close onto and firmly grip the wire, and then, as a unit, move across the face of the cut-off die and sever the gripped portion of the wire with an absolutely square cut-off face, and then carry and transfer the cut-off portion, now a workpiece, to a push-out station; and to so arrange this cut-off mechanism with respect to other parts that it will return for a succeeding cut-off operation during the transfer of the workpiece to the fabricating die. Other objects of the invention will become apparent from the following description and accompanying drawings, disclosing for the purpose of illustration, a preferred embodiment of the invention.

To these ends my invention consists in the cut-off and transfer mechanisms, having certain details of construction and combinations of parts, as will be hereinafter described and more particularly pointed out in the claims.

In the drawings, wherein like numerals of reference indicate like parts in the several figures;

Figure 1 is a transverse sectional view of a conventional header or the like, with this improved mechanism associated therewith, the parts in section being taken generally upon line 1—1 of Figure 5;

Figure 2 is a view of one end of the header;

Figures 3 and 4 are views of the die block, cutter slides, cutters and parts of the transfer mechanism, the parts in section being taken generally upon a line extending through the wire line and push-out line;

Figure 4a is a perspective view of one form of feed stop finger;

Figure 5 is a fragmentary plan view of a portion of a conventional header or the like;

Figure 6 is a sectional view of a portion of the header frame, die block and associated parts, taken generally upon line 6—6 of Figure 1;

Figures 7 and 8 are perspective views of two forms of cutter knives;

Figure 9 is a fragmentary perspective view of the cutter knives and slides;

Figure 10 is a fragmentary sectional view of the gib, slide and associated parts, the parts in section being taken generally upon line 10—10 of Figure 1;

Figure 11 is a transverse sectional view of the header or the like, the parts in section being taken generally upon line 11—11 of Figure 5, with the cutting mechanism omitted for clearing;

Figure 12 is a view of a portion of the header frame, feed cam and lever mechanism;

Figure 13 is a view of a portion of the transfer mechanism;

Figure 14 is another view thereof, the parts in section being taken generally upon line 14—14 of Figure 13;

Figure 15 is a view of a portion of the transfer mechanism, the parts in section being taken generally upon line 15—15 of Figure 11; and

Figure 16 is a view of the workpiece gripping portion of the transfer mechanism.

Referring to the drawings, 10 indicates the frame of a header, upsetting machine or the like, having a die block 11, in which is a fabricating die 12 or the like. This die block may be held rigid in the frame by any one of many convenient means well known in the art. Slidably held in the face of the die block 11, by a gib 15 or the like, are the two cutter slides 13 and 14, the former having a lug 17 at its outer end and the latter a similar lug 18 at its outer end, which are in line with each other. Between these lugs, and passing through an opening in the gib 15, is a rod 19, one end of which bears against the lug 17, and the other end of which passes through the lug 18, with a nut 20 threaded on the outer end thereof. When the die block 11 is to be removed from the header, the nut 20 on the rod 19 is tightened. This compresses the spring 23 and relatively the tension against the lugs 17 and 18 on the slides 13 and 14, so that they may later be brought together free from contact with the roll 59 and the adjusting screw 52. As so positioned, the entire die block unit may be removed from the machine. When replaced, the nut 20 is again loosened, allowing the spring 23 and the slides and associated parts to function as before.

The rod 19 is formed with a collar 21, which is 50 slideable within a hole 22 in the gib 15, and between which and the lug 18 is a spring 23. This spring exerts a slight tension upon the rod 19 and the lugs 18 and 17, so as to separate, when permissible, the inner ends of the slides 13 and 14. An adjustable stop pin 24 is in the path of

the lug 17 and limits movement of the slide 13 in one direction. Both slides are reciprocated by positively actuated mechanism. Such mechanism for moving the slides to the left, when viewed in their relative positions, as shown in Figure 1, comprises in part a rock arm 25, carrying a cam roll 59, fixed on a rock shaft 26, journaled in the frame 10, a rock arm 27, also upon the shaft, to which the connection 28 is hinged, by a pin 29 or the like. Journaled on the pin 30, fixed in the frame 10 or other rigid part, is a rock arm 31, to which the yoke 32 and cam roll 33 are journaled. The cam roll rides against the face of a cam 34 fixed upon the side shaft 35. Between the yokes 28 and 32 is a connection rod 36, threaded in the yoke 28 and passing through an opening in the yoke 32, with lock nuts 37 on its inner end.

Between the collar 38 on the connection rod 36 and the yoke 32, is a spring 39. Fixed to the frame 10 is a bracket 40, within which a plunger 41 is movably mounted and partly surrounded by a spring 42, between the screw 43 and a shoulder on the plunger. One end of this plunger engages a shoulder (Fig. 2) on the rock arm 31 and exerts a tension thereon that holds the cam roll 33 against the face of cam 34. The connection rod 36 and associated parts provide means for adjustment of the position of the rock arm 25, by which the slides 13 and 14 are moved in one direction (toward the left in Figure 1). These slides are moved in the opposite direction (to the right when viewed in Figure 1), from a cam 44 on the side shaft 35, through a rock lever 45 fulcrumed on the pin 30. Upon the rock lever 45 is a cam roll 46, which rides against the face of the cam 44 and is held thereagainst by a spring pin 48 pivotally connected to the rock lever 45 and slidable through a nut 49 threaded in the frame 10 (Fig. 1), being surrounded by a spring 47.

Movably mounted in the frame 10 is a plunger 50 connected by a link 51 with the rock lever 45, and whereby a reciprocating motion is imparted thereto from the cam 44. An adjusting screw 52 is threaded in the inner end of the cut-off plunger 50 and held in its adjusted positions by a nut 53. The outer end of this screw 52 abuts against the lug 18.

Secured to the inner adjacent end of each of the slides 13 and 14, by screws or other convenient means, is a cutter 16. In the inner end of each of these cutters is a recess 61 that is substantially the same shape in cross section as a portion of the workpiece. When the cam roll 46 is on the low portion of the cam 44, the slides 13 and 14 with the cutters 16 thereon, are in a position wherein the opening 57 between the inner ends of the cutters and formed by the recesses 61 of the same shape in cross section as the workpiece, is opposite and in register with the wire line, that is, the line of feed of the wire through the cut-off die 56. When the cam roll 46 is on the high portion of the cam 44, the slides 13 and 14 and the cutters 16 thereon, are in their right hand position (Fig. 1), the opening 57 then being in register with the push-out line 58. A push-out pin 54 at this station operates in a well known manner. The cam timing is such that when the plunger 50 is moving the slides and cutters from the wire line to the push-out line, the cam roll 59 will maintain its contact with the lug 17. When the cutters are moved in the reverse direction the source of power is applied thereto through the rock arm

25 and the cut-off plunger 50 moves rearwardly without losing contact with the lug 18.

When the slides are in the position wherein the opening 57 is in register with the wire line, and also when in register with the push-out line, the cutters 16 are moved and held apart a limited distance by the spring 23, thus allowing a free passage of the wire and workpiece therebetween.

10 The screw 52 in the plunger 50 is adjusted so that the cutter 16 connected with the slide 14 stops just short of the push-out line. During this action the rock arm 25 continues its movement for a slight over-travel, until the lug 17 on slide 13 engages the stop screw 24 and the cutter 16 thereon stops just beyond the push-out line. The spring 23 now holds these cutters slightly separated, pushing the slide 13 away from the slide 14, as determined by the stop pin 24, releasing their grip on the workpiece held therebetween.

20 The push-out pin 54, operating in a well known manner, projects the workpiece from between the cutters into the fingers of the transfer mechanism. The slides 13 and 14 are returned so that the opening 57 again registers with the wire line, through the action of the cam 34, arm 25 and associated parts. During the first portion of this return movement the slide 30 13 is actuated independently until the cutter thereon engages the cutter on the slide 14. Both slides and cutters now move as a unit until the opening 57 is approximately in register with the wire line. This is due to the fact that the rock arm 25 discontinues its pressure upon the slide 13, but the cut-off plunger 50 continues its movement for a slight over-travel. The spring 23 now separates the slides 14 and slide 13 and the cutters thereon a limited distance sufficient to permit the wire to pass freely therebetween until the end thereof engages a feed stop or the like. A portion of one form of feed stop 55 is shown in Figure 6, but any preferred form may be used within this invention. Immediately the end portion of the wire is between the cutters, the plunger 50 advances the slide 14 and the cutter attached thereto up to and in contact with the projecting portion of the wire. At the same time the cam 34 rocks the arm 25, advancing the slide 13 and its cutter until the latter contacts with the projecting portion of the wire. When so positioned, the two cutters firmly and rigidly grip that portion of the wire projecting beyond the face of the cut-off die 56. The slides now move the cutters and the workpiece held firmly therebetween from the wire line to the push-out line and during such movement the cutters sever the projecting portion of the wire from the wire length. The spring 39 compensates for any inaccuracy in the timing between the two cams 34 and 44.

25 In Figures 7, 4, 8 and 3, two forms of cutters are illustrated, the one shown in Figures 8 and 3 being designed for use in fabricating so-called long workpieces, and that shown in Figures 7 and 4 being designed for use in fabricating so-called short workpieces. These cutters are preferably constructed with a body portion, through which are openings to receive the fastening screws and a head portion 60 of greater thickness than the body portion, in the end face of which is the recess 61 to receive the wire, and to retain and carry it from one station to the other. For a workpiece longer than the thickness of the head portion 60, the feed stop 55 is

outside of the cutter, as in Figure 6. For a workpiece shorter than the thickness of the head portion 60 a feed stop 62 is used, having a relatively narrow tip 64. For such short length workpieces each cutter 16 is provided with a slot 63 of the desired depth, and into which projects the tip 64 of the feed stop that is in the path of the wire as it is fed through the cut-off die 56 into the opening 51 between the cutters when in register with the wire line. The thickness of the head portion 60 of these cutters is such that they give great stability to the projecting portion of the wire therebetween as the same is cut off from the wire length. This is one favorable factor in insuring a rigid holding of the wire during the cut-off operation, an essential in producing a square end workpiece. This relative thickness of the cutter head is possible in this invention because the workpiece is not presented to the fabricating die by the cut-off knives or cutters, as heretofore. In practice, it has been found that heretofore these cutters must be materially reduced in thickness to prevent interference with the advancing punch at the fabricating die. Herein the heads 60 of the cutters are relatively thick regardless of the length of the workpiece and rigidly support the workpiece and hold it against distortion while being severed.

On the rock shaft 26 is a rock arm 65, to which is secured a finger block 66, carrying a finger arm 67. On this finger arm is a latch 68 held by a bolt 69 under the tension of a spring 70. In the end of the arm 67 is a notch 71, open at one side, and over which projects an end of the latch 68, thus forming a notch 71 for the reception of a workpiece. The finger block 66 is adjustable on the rock arm 65 and the finger arm 67 on the finger block 66, and whereby the notch 71 may be moved into alignment with the center of the fabricating die 12, and thus bring the workpiece into position whereby its axis is coincident with the opening in the die.

Fixed on the frame 10 is a bracket 72 with a cap 73, in both of which is journaled a rock shaft 74. On one end of the shaft 74 is an arm 75, which is connected with the rock arm 65 by a link 76. Stop screws 77 and 78, threaded in a fixed part, are in the path of movement and engaged by the lug 79, on the rock arm 65, which limits the extent of movement thereof.

On the side shaft 35 is a cam hub 80, to which is secured the cam 81 by the screws 82, and a cam segment 83 adjustably secured thereto by the same screws 82.

Journalized on the pin 84, fixed in the frame 10, or other rigid part, is a rock arm 88, carrying a cam roll 85, which rides against the face of the cam 81 and cam segment 83, being held in such contact by a rod 89 connected by a pintle 90 with the rock arm 88 and slidable within a nut 86 in the bracket 87 secured to a fixed part and a spring surrounding the rod.

Between the rock arms 88 and 91 on the shaft 74, is an adjustable connection, comprising a rod 92, secured by a yoke 97 pivotally connected with the rock arm 91 and by a yoke 93 to the rock arm 88. Between the yoke 93 and a collar 94 on the rod 92 is a spring 95, which will yield when the lug 79 is in contact with the stop screw 78 when the apparatus is set for short workpieces. The timing of the transfer is such that the finger arm 67 is quickly withdrawn from its position in front of the fabricating die 12 and earlier or later to clear the advancing punch so that very short length blanks may be accommodated. For cut-

ting off workpieces that are longer than the thickness of the cutters, the notch 71 is carried above the push-out station. When in such a position it dwells while the workpiece between the cutters is carried over from the cut-off station in front of the push-out pin 54. The finger arm 67 now moves down and snaps onto the workpiece which rests in the notch 71 under slight pressure from the latch 68. After the blank has been pushed entirely out of the cutters and into the notch 71, the pusher pin 54 is withdrawn quickly and the arm arm 65 swings to the left, as shown in Figure 11, causing the finger arm 67 to swing downwardly carrying the workpiece in the notch 71 into register with the fabricating die 12, at which time the lug 79 contacts the stop screw 77 and is adjustable for position as the spring 98, surrounding the rod 89 will yield for such adjustment.

The cam 81 and cam segment 83 are utilized for transferring both short and long workpieces. When transferring a workpiece shorter in length than the thickness of the cutters, the finger arm 67, with the notch in its outer end, stops at the push-out station, and then the spring 95 is compressed to allow the full stroke of the cam 81 and cam segment 83.

When cutting off workpieces longer than the thickness of the cutters, the stop screw 78 is not utilized and the full stroke of the cam 81 and cam segment 83 is used as above described. The cam segment 83 is adjustable on the cam 81 through the screws 82 and slot 96, to give an adjustment of timing to the rock arm 65, so that the finger arm 67 can be returned from the fabricating die 12 earlier or later as may be required.

In Figure 4 the feed stop 62 is positioned closer to the die block than is the feed stop shown in Figure 3.

With the mechanism herein disclosed a workpiece is cut from a wire length with a severed face that is at a right angle to its length. Such right angle or square face is advantageous in future operations upon the workpiece. The end of the wire in the cut-off die also has a perfectly square face and becomes one end of the next succeeding workpiece cut therefrom, thus both ends of the workpiece are at right angles to the length of the workpiece and parallel with each other. In order to withstand the cut-off strain the parts upon which this duty comes must be relatively heavy and substantial to properly perform their functions. The workpiece when cut off, however, is relatively light. Therefore, the mechanism that transfers the workpiece from the cut-off mechanism to the fabricating dies is also relatively light. This differential in bulk, strength, etc., in favor of the transfer mechanism, is apparent in this invention. The cutters, plunger and associated parts are relatively heavy and strong in comparison with the finger arm 67, finger block 66 and rock arm 65, forming part of the transfer mechanism. In headers of this general character, heretofore made, the cut-off mechanism and the transfer mechanism are one and the same, and therefore, do not have a differential as to weight, strength, etc. Again, in such headers, the cut-off and transfer mechanism dwell a sufficient length of time in front of the fabricating dies to permit the workpiece to be removed therefrom and presented to the die before a succeeding feed of wire can take place. In the construction herein disclosed, however, immediately the transfer mechanism receives the workpiece the cut-off mechanism returns to the wire line

for another feed of wire, while the transfer mechanism carries the workpiece into line with the fabricating die. Thus the timing is easier and an increased speed of operation and output is achieved. In this mechanism the transfer arm is positively actuated through a link connected with the rock arm at a point distant from the axis of rotation of the rock arm, thus inducing ease and simplicity of action as distinguished from the conventional type of transfer mechanism, wherein the rock arm is fixed on a rock shaft and actuated thereby.

With this improved mechanism, the header is operated at an increased speed with resulting increased output. While operating under this increased speed, if perchance a workpiece when ejected from the fabricating die does not drop by gravity sufficiently fast to be out of the path of another punch, the transfer mechanism, carrying the new workpiece will engage it and assist in driving the workpiece downward. When the punches are horizontally shifted, the second punch at one side of the first punch is in a horizontal line and the workpiece only clears a single punch as it drops by gravity or is forced downwardly by the transfer mechanism. This differs in operation from the conventional type of header, where the two punches are in a vertical line and the workpiece ejected from the fabricating die must clear in its downward travel the second punch located below. Consequently, so far as clearing the fabricated workpiece is concerned, the header, by reason of this improved mechanism is virtually a single stroke machine, due to the second punch being at one side of the first punch and in substantially the same horizontal plane.

This invention may be embodied in forms other than that shown herein and be within the scope and spirit of the accompanying claims.

What is claimed is:

1. In a device of the character described; mechanism for cutting off a portion of a length of wire, rod or the like at one station, comprising in part companion cutters which receive and grip the wire therebetween during the cut-off operation and while so gripped cut off the gripped portion and carry it by a straight line movement to another station; and means for separating the cutters at both stations, whereby the wire and workpieces may move freely therebetween.

2. In a device of the character described; mechanism for cutting off a portion of a length of wire, rod or the like at one station, comprising in part companion cutters which receive and grip the wire therebetween during the cut-off operation and while so gripped cut off the gripped portion and carry it by a straight line movement to another station; and resilient means that actuate the cutters when in register with the said stations and whereby the cutters are separated at both stations a sufficient distance to permit the wire and workpieces to move freely therebetween.

3. In a device of the character described; mechanism for cutting off a portion of a length of wire, rod or the like, at one station, comprising in part a die block, plural slides mounted thereon to move in a substantially straight line, a cutter upon each slide, between which the wire is received and rigidly held while said portion is being cut off and thereafter carries it to another station, one slide having an over movement and one slide a short movement at each station, whereby the cross area of that portion of the cutters that receives the rod is greater than that of the rod and whereby the

wire rod and workpiece may move freely therebetween.

4. In a device of the character described; mechanism for cutting off a portion of a length of wire, rod or the like, comprising in part plural slides; a cutter associated with each slide and between which the wire is rigidly held during the cut-off operation; and means for separating the slides and cutters a limited distance as the wire enters between the cutters.

5. In a device of the character described; mechanism for cutting off a portion of a length of wire, rod or the like, comprising in part plural slides; a cutter associated with each slide and between which the wire is rigidly held during the cut-off operation; a member between said slides; and resilient means exerting a tension upon said member and whereby said slides are separated a limited distance as the wire passes between the cutters.

6. In a device of the character described; mechanism for cutting off a portion of a length of wire, rod or the like, comprising in part plural slides, each having a lug thereon; a cutter associated with each slide and between which the wire is rigidly held during the cut-off operation; a member passing through the lug on one slide and engaging the lug on the other slide; a spring between said member and one of said lugs, whereby tension is exerted on said member to separate said slides.

7. In a device of the character described; mechanism for cutting off a portion of a length of wire, rod or the like, comprising in part plural slides mounted in a rigid part to move in a substantially straight line; a fixed element holding the slides within said rigid part, a member passing through said fixed element, engaging a shoulder on one slide and passing through a part on the other slide, and tension means to separate said slides.

8. In a device of the character and for the purpose described; a slide; a cutter having a body portion and a head portion of greater thickness than the body portion with a blank holding recess in the end face of the head portion; and means for securing the cutter to the slide in engagement with the thinner portion of the cutter.

9. In a device of the character and for the purpose described; a slide; a cutter having a body portion, and a head portion of greater thickness than the body portion with a holding recess in the end face of the head portion, and a slot extending part way through the body and head portions to receive a stop member; and means for securing the cutter to the slide in engagement with the thinner portion of the cutter.

10. In a device of the character described; mechanism for cutting off a portion of a length of wire, rod or the like, at one station, comprising in part companion slides, a cutter on each slide which receives and holds the wire therebetween during the cut-off operation and transfers it to a second station; and separate cam actuated means for moving the slides in both directions with the cutters in engagement with each other.

11. In a device of the character described; mechanism for cutting off a portion of a length of wire, rod or the like at one station, comprising in part companion slides, a cutter on each slide which receives and holds the wire therebetween during the cut-off operation and transfers it to a second station; separate cam actuated means

for moving the slides in both directions with the cutters in engagement with each other, said cams permitting the slides and cutters to be separated slightly by means other than the cam means when the cutters are in register with each of said stations.

12. In a device of the character described; mechanism for cutting off a portion of a length of wire, rod or the like at one station, comprising in part, plural slides mounted to move in a substantially straight line, a cutter upon each slide, between which the wire is received and rigidly held while said portion is being cut off and thereafter carried to another station; and adjustable stop means for limiting the movement of the slides in one direction.

13. In a device of the character described; mechanism for cutting off a portion of a length of wire, rod or the like at one station, comprising in part companion slides, a cutter on each slide which receives and holds the wire therebetween during the cut-off operation and transfers it to a second station; and separate cam actuated means for moving the slides in both directions with the cutters in engagement with each other, each of the cam actuated means yielding to permit movement of the slides in the direction opposite to that actuated thereby.

14. In a device of the character described; mechanism for cutting off a portion of a length of wire, rod or the like at one station, comprising in part companion slides, a cutter on each slide which receives and holds the wire therebetween during the cut-off operation and transfers it to a second station; and separate cam actuated means for moving the slides in both directions with the cutters in engagement with each other, said cam means having a slight over movement to permit separation of the slides by independent means.

15. In a device of the character described; mechanism for cutting off a portion of a length of wire, rod or the like at one station, comprising in part companion slides, a cutter on each slide which receives and holds the wire therebetween during the cut-off operation and transfers it to a second station; and separate cam actuated means for moving the slides in both directions with the cutters in engagement with each other, one of said cam actuated means having a reciprocating member adjacent to its actuated slide and the other cam means having a rock member adjacent to its actuated slide.

16. In a device of the character described; mechanism for cutting off a portion of a length of wire, rod or the like at one station, comprising in part companion slides, a cutter on each slide which receives and holds the wire therebetween during the cut-off operation and transfers it to a second station; and separate cam actuated means for moving the slides in both directions with the cutters in engagement with each other, one of said cam actuated means including as a part thereof a reciprocating member adjacent to its actuated slide and the other cam means including as a part thereof a rock member adjacent to its actuated slide; and an adjustable member between the reciprocating member and its actuated slide to vary the relative positions thereof.

17. In a device of the character described; mechanism for cutting off a portion of a length of wire, rod or the like at one station, comprising in part companion slides, a cutter on each slide which receives and holds the wire therebetween

during the cut-off operation and transfers it to a second station; separate cam actuated means for moving the slides in both directions with the cutters in engagement with each other; and means for compensating for any inaccuracy in the timing of said separate cam actuated means.

18. In a device of the character described; in combination with companion reciprocating slides that carry a workpiece from one station to another and move toward and away from each other in the same plane as the slides reciprocate; of transfer means for carrying the workpiece from the last mentioned station to a station in a different plane.

19. In a device of the character described; in combination with companion reciprocating slides that carry a workpiece from one station to another and move toward and away from each other in the same plane as the slides reciprocate; of transfer means for carrying the workpiece from the last mentioned station to a station in a different plane through the arc of a circle.

20. In a device of the character described; mechanism for cutting off a portion of a length of wire, rod or the like at one station, comprising in part companion slides, a cutter on each slide which receives and holds the wire therebetween during the cut-off operation and transfers it to a second station; transfer means for carrying the workpiece from the last mentioned station to a station in a different plane through the arc of a circle; and means for actuating said slides and transfer mechanism, whereby the transfer mechanism will carry the workpiece to the last mentioned station while the slides are returning for the next succeeding workpiece.

21. In a device of the character described; in combination with slides that carry a workpiece from a cut-off station to a pushout station; of transfer means for carrying the workpiece through the arc of a circle from the pushout station to a delivery station that is positioned in a plane different than the delivery station and in a plane nearer the cut-off station than the delivery station; means for actuating said slides and transfer mechanism, whereby the transfer mechanism will carry the workpiece to the delivery station while the slides are returning to the cut-off station for the next succeeding workpiece; and means for controlling the transfer mechanism, whereby it will be held out of alignment with the workpiece while the workpiece is being partially ejected from the slides.

22. In a device of the character described; mechanism for cutting off a portion of a length of wire, rod or the like at one station, comprising in part companion slides, a cutter on each slide which receives and holds the wire therebetween during the cut-off operation and transfers it to a second station; transfer means for carrying the workpiece from the last mentioned station to a station in a different plane; means for actuating the slides and transfer mechanism, whereby the transfer mechanism will carry the workpiece to the last mentioned station while the slides are returning for the next succeeding workpiece; means for controlling the transfer mechanism, whereby it will be held out of alignment with the workpiece while the workpiece is being partially ejected from the slides and then moved into engagement with said workpiece.

23. In a device of the character described; mechanism for cutting off a portion of a length of wire, rod or the like at one station, compris-

ing in part companion slides, a cutter on each slide which receives and holds the wire therebetween during the cut-off operation and transfers it to a second station; and separate cam actuated means for moving the slides in both directions with the cutters in engagement with each other, one of said cam actuated means having a reciprocating member adjacent to its actuated slide, and the other cam means having a rock member adjacent to its actuated slide; in combination with transfer mechanism which carries the workpiece from the last mentioned station to a station in a different plane, the transfer mechanism being of lighter structure than that of the reciprocating member actuating slide. 15

24. In combination with a header having a die block with a cut-off station; a pushout station in substantially the same plane as the cut-off station, and a fabricating die in another plane that is also in a plane nearer the cut-off station than the pushout station; means for carrying a workpiece on a line with the push-out station to a point in register with the fabricating die, comprising a movably mounted finger-carrying member; and means for moving the finger from the push-out station to the fabricating die and from the fabricating die to the push-out station through an element connected with the carrying member and having a reciprocating motion. 20

25. In a device of the character described; a die block; mechanism for cutting off a length of wire rod or the like at one station on the die block, comprising in part companion slides, a cutter in each slide which receives and holds the wire therebetween during the cut-off operation and transfers it to a second station on the die block; and separate cam actuated means outside of the die block for moving the slides in both directions with the cutters in engagement with each other. 25

26. In a device of the character described; a die block; mechanism for cutting off a length of wire rod or the like at one station on the die block, comprising in part companion slides, a cutter in each slide which receives and holds the wire therebetween during the cut-off operation and transfers it to a second station on the die block; and separate cam actuated means outside of the die block for moving the slides in both directions with the cutters in engagement with each other; and means for holding said companion slides in relation to each other, whereby the die block and slides may be removed without change of position of the said cam actuated means. 30

RICHARD LESTER WILCOX.
